QUILL WITH SMALL CALIBER TUBING
INSERTED THEREINIra B. Hill, Kent, Ohio, assignor to Borg-Warner
Corporation, Chicago, Ill., a corporation of
Illinois

Application August 3, 1940, Serial No. 350,548

4 Claims. (Cl. 140—36)

This invention relates to wire weaving machines and more particularly to wire quill assemblies for such machines.

It is an object of this invention to provide a wire quill assembly incorporating improvements in the construction as well as added efficiency in the operation thereof. It is a more specific object to provide an improved arrangement for guiding a warp wire from the input end to the delivery end of a metal wire weaving machine quill. A still more specific object is the provision of an improved guide for conducting the warp wire from the rear end to the forward end of a wire quill having a driving gear embracing the same between the ends thereof.

Still another object is the provision of a novel method of fabricating a metal quill having the above qualifications.

Other and more specific objects, advantages and uses of my invention will become apparent from a reading of the following specification taken in connection with the appended drawing which forms a part thereof and wherein:

Fig. 1 is a broken away section view of the essential parts of a weaving machine incorporating a quill assembly representing a preferred embodiment of my invention;

Fig. 2 is a view of the quill assembly taken substantially on the line 2—2 of Fig. 1 with the surrounding parts of the machine removed and showing to advantage the arrangement of the small caliber guide tubing installed in the quill.

Referring first generally to Fig. 1, I have illustrated the essential elements of a wire fabric weaving head assembly of which the present invention is particularly adapted to form a part. This assembly is indicated generally at 10 and comprises my novel quill assembly 11 cooperating with a comb assembly 12 for producing a particular form of wire fabric indicated generally at 13.

With general reference only to the operation of this weaving head 10 in the production of a piece of fabric, a pair of warp wires 14 are fed along my novel guide arrangement indicated generally at 15 and extending from the inlet end of quill 16 to the discharge or twisting end 17 thereof. Quill 16 is provided intermediate the ends thereof with a gear 18, this gear being rotated by means of a reciprocating rack 20 for producing with the cooperation of comb assembly 12 integrating twist 21 between the warp wires 14 for the purpose of locking in place the flap or ribbon-like filler wires 22.

From the above it will be appreciated that if

the integrating twists 21 are to be evenly and otherwise properly formed it is necessary to provide an efficient guide means for conducting the warp wires 14 from the rear end of the quill to the forward discharge or twisting end 17 thereof. I have observed from experience that in the absence of the necessary guiding means the warp wires are unevenly and improperly fed along the quill resulting in an irregular fabric having objectionable optical characteristics. Where the fabric is intended for use as window screen these objectionable optical characteristics render the same unsatisfactory for this purpose.

The present invention is directed particularly to the novel arrangement of guide means 15 for efficiently guiding the warp wires 14 from the inlet ends of the quill 16 to the discharge or twisting ends 17 thereof, no further description of the weaving machine proper being deemed necessary to an appreciation of the present invention particularly since reference may be had to copending applications of Ewing Serial No. 239,240, now Patent No. 2,223,317, and Heinze Serial No. 239,257 filed November 7, 1938, now Patent No. 2,214,054.

My novel guide arrangement indicated generally at 15 comprises essentially a pair of small caliber tubes 25 extending from one end of the quill 16 to the other and adapted to receive the warp wires for passage therethrough. The arrangement is particularly characterized by the fact that tubes 25 are positioned below the periphery of the quill 16 in channels or passages 26 formed for their reception. Tubes 25 pass through the central portion of gear 18 inwardly of the gear teeth. It is of particular importance to note that channels 26 enter the forward nose 17 of quill 16 at opposite ends of that diameter on which the wedge-shaped extremity of nose 17 lies and extends in a spiral-like path along the periphery of the quill to points of discharge at the opposite ends of a second diameter positioned ninety degrees with reference to the first mentioned diameter. This arrangement has been found to have particular advantages both in fabrication and in resulting operation of the assembly.

Tubes 25 are preferably, though not necessarily, of metal and in certain instances may be 50 that tubing known commercially as "hypodermic" tubing.

A preferred method of fabricating the present assembly shown in the drawing comprises first providing a cylindrical quill body 16 with channels 26 in the periphery thereof. Next installing

the small bore metal tubing 25 preferably by the technique commonly known as "sweating." This involves placing the tubing in the channel 26 and fixing the same therein by melting thereabout as with a soldering iron, a limited quantity of a solder or metal indicated generally at 27 having a higher melting point than the melting point of either the metal of the quill body or that of the tube being installed. Following this operation the gear 18 is pressed on to the quill body and fastened thereto as by pin 19.

It will of course be understood that while the above is believed to present a novel and advantageous method of providing the present quill assembly, the same may be fabricated in other ways coming within the broader scope of my invention. For example, the quill body 16 and gear 18 may be fabricated from a single piece of stock, the channels 26 in the periphery of the quill periphery communicating with passages formed through the central portion of the quill body.

The warp wires 14 may be supplied to the quill from any suitable source such as supply spools (not shown) being led to the rear ends of the guides 15 through a tensioning assembly indicated generally at 30, the details of which are covered in a separate co-pending application Serial No. 350,549, filed August 3, 1940.

While I have disclosed my invention in connection with certain specific embodiments thereof, I contemplate other equivalent arrangements and desire that the above be considered by way of example rather than by way of limitation and that my invention be defined by the appended claims which should be given a scope as broad as permitted by the prior art.

I claim:

1. In a weaving machine warp wire feeding quill assembly including a generally cylindrical body, a gear embracing said body intermediate the ends thereof, said body being formed with a recessed channel in the periphery thereof, said channel extending generally axially along said body, said gear being formed with a passage generally centrally located with respect to the teeth of said gear, said passage merging with said channel, and tubing having a caliber of the order of the diameter of said warp wire installed in said channel and passage and functioning as a guide for conducting said wire between the ends of said quill.

5 2. In a weaving machine rotatable quill assembly for feeding a pair of warp wires and twisting the same together adjacent the forward end of said quill with a predetermined tightness, a generally cylindrical-shaped quill having a gear intermediate the ends thereof for rotating the same, said quill being formed along the periphery thereof with a pair of generally diametrically opposed channels extending generally axially from the input end to the twisting end of said quill, said gear being formed with a pair of passages generally centrally with respect to the teeth of said gear and in communication with said channels, a pair of metal tubes having a caliber corresponding to the diameter of said warp wires received within said channels and passages for conducting said warp wires from the input end of said quill to the twisting end thereof.

10 3. In a weaving machine, a wire feeding quill assembly including a generally cylindrical quill, said quill being formed with a pair of opposed channels extending in a hexical-like path between the two ends of said quill, said channels beginning at one end of said shaft on opposite ends of a first diameter and terminating at the opposite ends of a second diameter at the discharge end of said quill, said last named diameter being disposed at an angle of approximately 45° to said first named diameter, and small tubing of a caliber corresponding to said wire received in each of said channels for conducting the wires between the ends of said quill.

15 4. In a wire screen weaving machine rotatable quill assembly for feeding and twisting together a pair of warp wires adjacent the forward end of said quill, said assembly including a generally cylindrically shaped elongated body, a driving gear intermediate the ends of said body having a pitch diameter greater than the diameter of said body, a pair of generally parallel diametrically opposed channels extending generally axially along said body from the rear inlet end thereof and centrally within said gear to the discharge twisting end of said body, a pair of metal tubes 20 having a caliber corresponding to the diameter of said warp wires received within said channels and functioning to conduct said warp wires from the inlet end of said body to the twisting end thereof.

50 I.RA B. HILL.
